[57] CLAIM

The ornamental design for a chair, as shown and described.

DESCRIPTION

FIG. 1 is a left top front perspective view of a chair showing the new design;

FIG. 2 is a left side elevation view thereof;

FIG. 3 is a front side elevation view thereof;

FIG. 4 is a top plan view thereof;

FIG. 5 is a rear side elevation view thereof; and,

FIG. 6 is a bottom plan view thereof.

The broken lines showing in FIGS. 1-3 and 5 are for illustrative purposes only and form no part of the claimed design.
